United States Patent Office

Des. 224,054

Patented June 27, 1972

224,054

XEROGRAPHIC REPRODUCTION MACHINE OR THE LIKE

Dan R. Derby, Cupertino, Calif., and Ruediger W. Knodt,
Rochester, and Homer Korn, Webster, N.Y., assignors
to Xerox Corporation, Stamford, Conn.

Filed Sept. 21, 1970, Ser. No. 25,070

Term of patent 14 years

Int. Cl. D16—03

U.S. Cl. D61—1

FIG. 1

FIG. 2

FIG. 3

FIG. 5

FIG. 4

FIG. 7

FIG. 6

FIG. 1 is a right hand front perspective view of a xerographic reproduction machine or the like showing our new design;

FIG. 2 is a left hand front perspective view thereof;

FIG. 3 is a top plan view thereof;

FIG. 4 is a front elevational view thereof;

FIG. 5 is a rear elevational view thereof;

FIG. 6 is a left hand elevational view thereof; and

FIG. 7 is a right hand elevational view thereof.

We claim:

The ornamental design for a xerographic reproduction machine or the like, as shown.
